UNITED STATES PATENT OFFICE.

EPHRAIM HOWLAND, OF PONTIAC, MICHIGAN.

LOADING, CONVEYING, AND DUMPING DEVICE.

No. 811,928.

Specification of Letters Patent.

Patented Feb. 6, 1906.

Application filed August 29, 1904. Serial No. 222,505.

To all whom it may concern:

Be it known that I, EPHRAIM HOWLAND, a citizen of the United States, residing at Pontiac, county of Oakland, State of Michigan, have invented a certain new and useful Improvement in Loading, Conveying, and Dumping Devices; and I declare the following to be a full, clear, and exact description of the invention, such as will enable others skilled in the art to which it pertains to make and use the same, reference being had to the accompanying drawings, which form a part of this specification.

My invention relates to improvements in portable loading and dumping machines or conveyances for loading and carrying dirt, sand, gravel, manure, and other like material by which the same can be loaded by scrapers or similarly-operated devices, and also devices whereby the same can be unloaded without the use of manual labor, and also devices whereby the largest amount of material can be carried on the shortest wheel-base, thereby affording a greater facility for maneuvering in proportion to the load and with the least amount of trouble and expense; and it consists in the combinations hereinabove described and claimed.

In the drawings, Figure 1 is a perspective view of the entire device, except that the tongue and means for guiding the front wheels are omitted. Fig. 2 is a plan view. Fig. 3 is a front elevation. Fig. 4 is a view of the windlass and engine connections.

Similar letters refer to similar parts.

A A represent the sills of the body proper; W W, the wheels upon which the same is conveyed.

B B are the sides, which otherwise, except as being rights and lefts, are similar in construction and are solidly built up from the sills A A by means of vertical posts and side boards in the usual manner. A cross-partition C separates the space inclosed by the sides B B into two parts, the partition being located a short distance from the front. The two spaces into which the contents between the side pieces B B are thus divided by the partition C are open at both front and rear. The front portion is floored at D, whereas the rear portion is open, except when closed by means of the unloading devices hereinafter to be described. Upon the floor D is mounted an ordinary gas-engine E of the requisite power, possessing all of its usual appliances and carrying upon its shaft a band-pulley e.

The two forward posts b b' extend above the sides B B and are connected by cross bars or girths b²b². Upon these, mounted in journals, is a shaft G, and revolvably mounted upon said shaft is a windlass F. The shaft G carries a band-wheel G', and a band G² connects the same to the pulley e. This band is not ordinarily tight, but sags from the pulley e, whereby the band-wheel G' is not driven thereby until an idler-pulley H tightens the band in the usual way by means of a bent hand-lever H'. The windlass F is not only revolvably mounted on the shaft G, but is slidably mounted thereon, and when, as shown in Fig. 3, it is moved to the left it can revolve freely upon said shaft as a bearing; but when moved to the right a clutch engagement, such as pin g', engaging in a notch g², will compel the windlass to revolve with the shaft, and thus be driven by the band-wheel G', fixed upon the shaft when the belt is tightened. A rope J, one end of which is fixed to the windlass F and partially or wholly wound thereon, is operated by the windlass F and used as hereinafter described.

As the construction of the gas-engine and the windlass proper, aside from the details hereinbefore given, is common to such engines and hoisting devices, it is unnecessary to further describe them or to illustrate them.

Pivotedly attached to the rear end of the main frame at a is a bridge adapted to be raised and lowered in the manner hereinafter described and forming a device for loading in connection with the scraper A², which may be drawn by the rope J up the bridge and, if desired, to the front end of the rear compartment adjacent to partition C. The bridge has triangularly-formed sides a' a', with triangularly-formed telescope ends a², which when the bridge is raised, as hereinafter described, pass inside of the sides B B and when the bridge is lowered close off any opening that would otherwise exist. Upon one end, adjacent to the pivot a of the bridge A', is a gallows-frame consisting of two upright posts, one upon either side, with a cross-bar firmly attached thereto at the top. Proper braces a³ connect the sides of the frame with the triangular side pieces a' a', thereby rendering the whole structure rigid. The side pieces a' a' have terminal wings a⁴, which are flared outwardly, as shown in the plan view. Also the outer edge of the bridge A' is made sharp at a⁵ and preferably bound with iron, and when the apparatus is in place for load-

ing and the bridge dropped to the ground the edge naturally digs into the ground and the bridge forms a brace, whereby the backward movement of the apparatus is prevented. The bridge is formed with the frame A', leaving the bottom open, but pivoted in the bottom is a dump-board K. This dump-board is pivoted upon an iron cross-bar k , passing underneath the same and a short distance from its front end, for the reason hereinafter stated, and is raised and lowered in the manner hereinafter to be described. As shown in the plan view, Fig. 2, there are two similar dump-boards K' K², also pivoted on round iron pivots $k' k^2$. All of these three dump-boards are held in position, forming a bottom to the box or dirt-receptacle, by means of the apparatus herein-after described. In view of keeping the body as low as possible and yet giving the dump-boards the requisite inclination for depositing the load, the pivot-bars upon which they turn are located back from the front edge of the dump-boards—say, comparatively, from one fourth to one-third of their length, or at a point sufficiently far to insure the heavier end with its load overbalancing the lighter end and its load, thus securing a prompter delivery of the load by reason of the greater inclination thus secured. This is quite important with the dump-board in the bridge, because the bridge must be long enough to assure an easy ascent and also preferably long enough to carry a considerable load, as this load balances the load forward of the rear axle and enables much more of to be carried upon the rear axle, which is desirable. As the bridge, therefore, is long, comparatively, dropping the bridge itself would not insure prompt delivery of the load. Therefore the dump-board is pivoted back of its front edge for the purpose of securing an inclination requisite for delivering the load. A shaft M is journaled upon either side of the sides B B and is controlled by a handle m , partially cut away, and has upon either side cranks $m' m'$. Attached to the outer end of these cranks are ropes m^3 , passing over pulleys m^4 and firmly attached to the outer end of the dump-board K at m^5 by means of a cross-piece extending beyond the sides A' of the bridge or the sills. As shown in Fig. 1, the dump-board K is closed. Journaled upon the front end and top of the girths $b^2 b^3$ is a shaft N, carrying duplicate cranks $n n$ and controlled by lever n' . A rope connects the outer end of the cranks n with cross-pieces attached to the dump-board K', and, as shown in position in the drawings, the dump-board K' is shown closed. In the dotted lines in Fig. 1 the dump-board K² is shown partially open, the position of the rope when the dump-board is thus open being also shown in dotted lines.

It will be noted that when closed the pull of the crank n is past the center, so that they

operate as a toggle-joint to resist the opening; but a slight amount of force will suffice to pass the ropes over the center of the movement, and thus drop the dump-board. A similar shaft P, having cranks $p p$, is connected in exactly the same way with the rear end of the dump-board K². It will be noted that thereby each one of the dump-boards can be dropped, there being no reach, in the ordinary acceptation of the term, between the front and rear axle. A proper hand-operated ratchet is shown at R on the shaft G.

The operation using this device is as follows: The rope J, which may be of any assignable or reasonable length, is hooked into the bail of the scraper A², and the drum F being allowed to revolve freely the scraper is drawn to any position which may be desired, the drum being then clutched with the shaft G and the engine started, or if the engine be still under motion, the idler H being thrown into connection with the band, the windlass F is thereby operated to draw the scraper toward the bridge A', engaging whatever material is to be loaded. This is filled and drawn to and up the bridge to the front end of the rear compartment near the partition C and there dumped. The windlass is then detached from the clutch and the scraper is drawn back for reloading, and the operation is repeated until the whole body is filled. Then the bridge itself is filled as far as possible, when by detaching the hook of the rope from the bail of the scraper and attaching it to the top of the gallows-frame and operating the windlass the bridge A' can be raised up to a level with the floor of the body and held there with its load during the transportation of the entire load to the place where wanted. On arriving at the place where the load is to be dumped the shafts M and N are operated in the manner indicated and drop the dump-boards K, K', and K², whereby the whole load is almost instantly dumped and the device drawn from over the dumped load to be returned to the place for reloading.

It is obvious that many variations of details may be made without departing from the principle of my invention.

Having thus described my invention, what I desire to claim is—

1. In a combined loading conveying and dumping device, the combination of a body mounted upon traveling wheels, a motor mounted on the front end of said body, a windlass to be operated by said motor, means for gathering a load operated by said windlass, a bridge pivotally attached to the rear end of said traveling device adapted to operate as a brace against the resistance of the loading pulls, and to be raised when loaded, substantially as described.

2. In a combined loading, conveying and dumping device, the combination of a body adapted to travel upon wheels, motor means

- 25
carried thereby adapted to draw the material to be loaded thereonto, a bridge pivoted to the end adapted to serve as a brace, and means connecting said bridge and said motor means whereby the bridge may be hauled up 5 and held in position to support a part of the load during the movement of the vehicle, substantially as described.
- 30
3. In a combined loading conveying and dumping device, the combination of a body member adapted to travel upon wheels, means mounted thereon whereby the material to be loaded can be drawn into and dumped upon the floor thereof, a bridge adapted to form a brace and also as means for controlling the 15 passage thereover of the loading means, the bottom of said device and said bridge having dump-boards and means for controlling the same, substantially as described.
- 35
20 4. In a combined loading conveying and dumping device, in combination with the body mounted upon traveling wheels, a bridge pivotally attached to the rear end of said body, means for raising and lowering
- the bridge, and a pivoted dump-board located in said bridge, affording when dropped an inclination of greater angle than the bridge when the same is dropped, and means for operating said dump-board, substantially as described.
- 30
3. In a combined loading, conveying and dumping device, the combination of a body member adapted to travel upon wheels, a bridge member pivoted to one end of said body member, dump-boards pivoted to and forming a part of the floor portion of said members, said boards being so adjusted that one end is raised while the other descends under the influence of the load, and means carried by said body portion whereby said 40 boards may be raised and lowered, substantially as described.

In testimony whereof I sign this specification in the presence of two witnesses.

EPHRAIM HOWLAND.
